UNITED STATES PATENT OFFICE

LESLIE F. CORRIGAN, OF CHICAGO, ILLINOIS

WALL CABINET

Application filed June 10, 1929. Serial No. 369,572.

This invention relates to wall cabinets, such as medicine cabinets or closets usually provided in bathrooms and the like. It has for its objects to produce an interiorly illuminable cabinet; to provide a simple and practical built-in lighting device in which the lamp is automatically lighted when the door of the cabinet is opened and the light likewise extinguished when the door is closed; and to 10 attain certain other advantages as will hereinafter more fully appear.

The invention consists in the novel construction and in the parts and combinations and arrangements of parts as hereinafter described and set forth in the appended claims.

In the accompanying drawing, forming part of this specification and illustrating a practical adaptation of the invention,—

Fig. 1 is a perspective view of the cabinet with the door closed and portions of the door being broken away to illustrate certain interior arrangements of the cabinet;

Fig. 2 is a vertical section through the cabinet, the section being taken on or about the line 2—2 of Fig. 4;

Fig. 3 is a vertical section taken on or about the line 3—3 of Fig. 2;

Fig. 4 is a horizontal section taken on or about the line 4—4 of Fig. 3; and

Fig. 5 is a fragmentary section, on an enlarged scale, taken on or about the line 5—5 of Fig. 3.

Referring now to the drawing, the numeral 10 designates the cabinet, which may be constructed of metal or any other suitable material. As shown, the cabinet is provided at opposite ends with vertical compartments 11 which extend from top to bottom of the cabinet, said compartments being connected at the bottom of the cabinet by a transverse compartment 12. These compartments may be conveniently produced in a hollow walled unitary structure for a cabinet which may be mounted on the outside of the wall in a room, or said compartments may be provided in the framework for a built-in cabinet structure.

In the preferred structure the compartments or chambers 11 are divided from the main compartment of the cabinet by walls 13 having panels of frosted glass or the like 14

extending from top to bottom of the cabinet. These panels are preferably removable so that access may be readily had to the compartments or chambers 11, and for this purpose, said division walls 13 are provided with 55 rectangular openings having rabbeted marginal portions 15 in which said panels 14 are seated. The panels 14 are releasably held in place by the abutting end portions of shelves 16, which are removably seated on lugs 17 or other suitable supporting brackets provided on the division walls 13.

Any suitable arrangement of lamps may be provided in the compartments or chambers 11, the light from which will be transmitted and diffused through the panels 14 into the main compartment of the cabinet. It is preferable to provide sockets 18 in the lower portions of the compartments 11, in which sockets may be placed elongated tubular electric light bulbs 19. Said sockets 18 may be tapped into an electrical circuit in any obvious manner, and any suitable switch may be provided that will act automatically to close said circuit when the cabinet door is 65 opened and break said circuit when the door is closed. Such an arrangement is shown more or less diagrammatically in Fig. 5 of the drawing. According to this arrangement the switch comprises a reciprocatory member 20 which slides through a guide bracket 21 on the division wall 13 and through an opening 22 in the front wall 23 of the cabinet. Said member 20 is provided with a collar 24 and it has a spring 25 sleeved thereon between said collar 24 and said guide bracket 21, said spring 25 acting to move said member 20 outwardly. In the closed position of the cabinet door 26 the outer end portion 27 of the member 20 is engaged by the inner face of the door and said member 20 is held in retracted position against the tension of the compressed spring 25. When the door 26 is opened the spring 25 moves the member 20 outwardly, and at the same time 70

a lateral projection 28 at the inner end of said member 20 is brought into engagement with a normally opened spring terminal contact member 29 and moves the latter into engagement with a cooperative companion ter- 75 80 85 90 95 100

minal member 30, and thereby closes the electrical circuit through the lamps 19.

By the provision of the illuminable compartments at the ends of the cabinet and extending from top to bottom thereof, the interior of the main compartment of the cabinet is illuminated sufficiently to observe the contents of the cabinet without necessitating the illumination of the room, and the provision of an automatic switch controlled by the opening and closing of the door of the cabinet is of material advantage.

Obviously, the structure admits of considerable modification without departing from the spirit and scope of the invention as defined by the appended claims. The invention, therefore, is not limited to the specific construction and arrangements shown in the accompanying drawing.

Having thus described my invention, what I claim as new and desire to secure by Letters Patent is:

1. In a cabinet of the character described, a main storage compartment having a series of removable shelves, an illuminating chamber at the side of said main compartment and extending from top to bottom thereof, and a dividing wall between said main compartment and said illuminating chamber including a removable light transmitting panel retained in place by abutting end portions of the shelves of the cabinet.

2. A cabinet of the character described comprising a housing divided into a main storage compartment at the middle thereof and auxiliary compartments at opposite ends thereof, said auxiliary compartments extending from top to bottom of the cabinet, the division walls between said main compartment and auxiliary compartments including removable light transmitting panels, shelves removably supported on the division walls between said main and auxiliary compartments with their end portions abutting said panels in retentive relation thereto, and means for illuminating said auxiliary compartments.

In testimony whereof I have signed my name to this specification.

LESLIE F. CORRIGAN.
